UNITED STATES PATENT OFFICE.

ROBERT W. VAIL, OF NEW YORK, N. Y.

NON-SINKABLE SHIP.

1,274,821.

Specification of Letters Patent.

Patented Aug. 6, 1918.

Application filed June 13, 1917. Serial No. 174,488.

To all whom it may concern:

Be it known that I, ROBERT W. VAIL, a citizen of the United States, residing at New York, in the county of New York and State 5 of New York, have invented a new and useful Non-Sinkable Ship, of which the following is a specification.

My invention has for its object a ship having the ordinary type of hull within which 10 are attached certain arrangements, through which, if the ship is torpedoed rending a hole or holes in its hull above, at or below the water line, the amount of sea water allowed to enter through same will be limited, by 15 these arrangements, to an amount not sufficient to tend to sink the ship or to endanger the ship in any way or to prevent her further passage to her destination.

It is a further object of my invention that 20 these internal ship arrangements which constitute my invention (in correlation with the ship's hull, shall be designed to be easily removable and replaceable so that, if torpedoed and perforated they may be easily and 25 quickly replaced upon arrival at port or may be repaired at sea. This object, the possible removal of the new internal parts of ship, without injury to hull, saves the valuable hulls for further use, with internal arrangements 30 changed to normal conditions, after the war.

The primary object of this nonsinkability by said "internal arrangements" is the trans-oceanic safeconduct of food, clothing and 35 other useful articles as shall be allowed to be delivered by the United States Government to foreign peoples and the safeconduct of the ship itself. A still further object of my invention is the protection of cargo against 40 wetting and injury by sea water, if ship is torpedoed, tearing hole or holes in hull, and sea enters through said apertures and within the interior of hull of ship.

I attain the objects of my invention by the 45 mechanism illustrated in the accompanying drawings, in which—

Figure 1 is a vertical section on a longitudinal median line through a ship equipped with my invention;

50 Fig. 2 is a similar section with further parts of the invention shown in elevation;

Fig. 3 is a section on a line in front of bulkhead 31;

Fig. 4 is a section on a line in the rear of 55 this bulkhead and through the revolute

drum 49, and showing cargo-carrying drum 51 in elevation;

Fig. 5 is a transverse section in front of the engine room;

Fig. 6 is a transverse section through the 60 engine room;

Fig. 7 is a top plan of the invention with the deck removed;

Fig. 8 is a horizontal longitudinal section partly in elevation of a ship equipped with 65 my invention;

Fig. 9 is an end view of one of the revolute cylinders;

Fig. 10 is a detail view of one of the metallic plates for bracing the engine room; 70

Fig. 11 is a vertical transverse section through the ship showing a modified form of the protecting frame of the engine room in elevation;

Fig. 12 is a diagrammatic view of the ship, 75 illustrating the correct proportions of the apparatus as applied to such a vessel as the Transylvania, illustrating the use to which the invention is put;

Fig. 13 is a detail end elevation of the 80 water-tight bulkheads;

Fig. 14 is a general side elevation of a boat showing the means for steering the same and the propelling means;

Fig. 15 is a detail of the means of preventing the shifting of the water-tight bulkheads aforesaid; 85

Fig. 16 is a fragmentary top view of the capstan whereby the water-tight exterior drums are rotated in an emergency; and 90

Fig. 17 is a longitudinal vertical section of the cargo carrying drum showing the watertight doors.

Like characters of reference designate like parts throughout the several views. 95

Referring to the accompanying drawings illustrating my invention:

1, designates the keel of the ship; 3, the stern post; 4, the outer hull; 5, the inner hull; 8, the deck of the ship; 9, structural 100 steel bracing for the outer hull; 10, structural steel bracing for the inner hull; 11, deck supporting girders, and 6, sealed air compartments between the inner and outer hulls. The parts above enumerated may 105 conform to the usual shipbuilding practice. Sleeping quarters, 14 and 15 for the crew may be arranged at any suitable portions of the ship. Watertight walls 12 and 13 are provided between sleeping quarters 14 and 110 110

15 respectively, and the rest of the interior of the ship.

I provide weight-sustaining segments 16 and 17 of a ring of structural steel, divided 5 into equal parts as at 18. Ring 16 is attached to the bracing 10 of the inner hull by any suitable fastening members 19, as shown in Fig. 8. Upper ring section 17 is removable but is secured in place by the approximately 10 U-shaped structural part 22, which is fastened at 23 to member 17, and at 26 to member 25, as shown in Figs. 3 and 4.

I provide novel revoluble cylinders 49, which are suitably reinforced and are watertight, and which revolve on the horizontal axes provided by the stationary trunnions 35, being mounted thereon by means of bearing ring 50. Member 40 is a stationary shaft upon which is mounted the sleeve 39, 20 to which in turn is mounted the radially disposed structural bracing 42, which is suitably pinned or keyed to shaft 40, and member 42 in turn supports cylinders 35. Member 60 is a structural bracing member 25 which reinforces the watertight stationary drum 51, which carries the cargo, and which is further protected by the outer stationary cylinder 52. 47 is a watertight protective disk attached to member 35, as shown in Fig. 30 13. Member 31 is a stationary protective wall, having brace portions 32, secured to frame 30.

Member 60 operates to relieve the torsion strain caused by the weight of cargo within drum 51.

Referring to Fig. 2, I provide suitable grooved rings 64 which are fitted over and secured to revoluble cylinder 49. Suitable cables 68 encircle ring 64, and are secured to 40 the rings at knobs 70. These cables 68 provide a means for revolving the cylinders 60 either by power from the engines or by hand power by means of a suitable capstan 402.

Referring to Fig. 1, 77 designates a cylinder forming an encircling wall of the engine room, which may be disposed in any suitable portion of the ship, as correctly illustrated in Fig. 11. I provide four or more supporting plates 71, positioned 45 lengthwise of the ship, parallel to each other, and at right angles to the structural ship braces 10, on which they rest, as shown in Fig. 6. Plates 71 are provided with slots 74 in their lower portion, and with a large 50 apertured portion 72, as illustrated in Fig. 10. These plates serve as bracing members for the entire engine room.

Members 78 are stationary disks attached to cylinder 77. It is within the contemplation 60 of my invention to also provide when desired spherical segments 79 as shown in Figs. 5 and 6, as an outer protective wall for the engine room. Members 79 engage shafts 83.

65 Cast on circular segments 79 I provide

grooved annular rings 87 which are encircled by a suitable cable 89 by means of which the spherical segments 79, as shown in Figs. 5 and 6, may be revolved.

The subject matter of Figs. 5 and 11 are 70 identical except that in Fig. 5 the revoluble walls of the engine room are segments of a sphere, while in Fig. 11 a cylindrical form of protective wall is provided.

Any suitable smoke stack 90 and ventilators 91 may be provided. 75

Cables 89 are led through suitable apertures 93 in the deck and thence to any suitable means for operating them.

I provide suitable platforms 94 to facilitate inspection of the revoluble cylinders 49.

Referring to Figs. 13 and 17, I provide cover 96 which may be made in watertight connection with member 52 by means of fastening members 97. 96 is a suitable cover 85 or door mounted on pivot 100 and secured in water-tight engagement by means of fastening members 97.

76 shown in Fig. 8 designates a suitable flooring for the engine room, supported on 90 member 71. I may provide any suitable radially disposed braces 53 as reinforcing members for members 51.

Referring to Fig. 2, hook 401 is adapted to engage in any of the transverse bars 404 95 which I provide on the exterior surface of the revoluble cylinders 49. This device affords a means of rotating the cylinders in an emergency in the event that the usual encircling cable is damaged and rendered useless. 100

Referring to Fig. 14, the rudder R may be operated by a suitable chain or cable 406, disposed in a channel beneath or at one side of the revoluble cylinders 49. 105

Referring to Fig. 15, I may provide protective walls 31 with lugs 408, or with pins 409 to secure it in a stationary position.

I provide a suitable water pipe arranged as shown in Fig. 1 to permit of the pumping of water from the bottom of revoluble cylinders 49 in the event water should enter that portion of the ship. 110

Figs. 11 and 12 illustrate my invention applied to a ship approximately 548 feet 115 long, 65.5 feet wide and having a depth of 42 feet. The dotted line 110 designates approximately the normal water line. The dotted line 108 designates approximately the load water line. If the ship is pierced, as at portion 88 of the hull, the revoluble cylinder 49 may be rotated so that the damaged portion 69 will be uppermost, thus preventing water from entering and sinking the ship. Suitable pumps attached to pipe 109 may be operated to remove any water that has entered cylinder 49 prior to its being rotated to the position shown in Fig. 12. In the latter position the revoluble cylinders 49 are in a position where repairs 120

125

may be easily made by the ship's mechanics. The amount of water that will enter because of the torpedoing will be insufficient to sink the ship or to seriously endanger her. Each 5 set of walls with the revoluble cylinders and accessory parts is removable. Removable sections of the deck should be provided to facilitate repairs.

What I claim is:

10 1. A ship having cargo-protecting cylinders revolubly mounted on a horizontal axis.

15 2. In a ship, the combination of a cargo-carrying drum, a revoluble cylinder inclos- 50 ing the drum and means for rotating the revoluble cylinder.

20 3. In a ship, the combination of a plu- 55 rality of cargo-carrying drums, stationary outer drums, and revoluble cylinders spaced from and encircling the outer drums and means for revolving the cylinders on axes parallel with the keel.

25 4. In a ship, the combination of water 60 tight upright walls, trunnions mounted in the walls, protective revoluble cylinders revolubly mounted on the trunnions, protective stationary drums within the revoluble cylinders, and inner stationary cargo-carrying drums within the aforesaid stationary 65 drums.

30 5. In combination with the device de- 70 scribed in claim 4, a pipe extending through the water tight wall, trunnions and stationary drums to the interior of the revoluble drum to permit of the pumping of water from that member.

35 6. In a ship, the combination of an en- 75 gine room having protective walls, and means for rotating said walls.

40 7. In a ship, the combination of an engine 80 room having a protective segmental wall, and means for rotating said wall.

45 8. In a ship, the combination of station- 85 ary cargo-carrying compartments supported from axial members, revoluble cylinders in- closing said compartment revolubly mount-

ed on the aforesaid axial members, and means for revolving said cylinders.

9. In a ship, the combination of cargo-carrying stationary drums, protective revoluble cylinders, transverse bars mounted on the circumferential portion of said cylinders, a cable having a hook attached to it, the hook being adapted to engage in the transverse bars mounted on the revoluble 55 cylinders, and means for exerting power on the cable.

10. In a ship, the combination of a plu- 60 rality of stationary cargo-carrying members protective covers spaced from and revolubly mounted over the cargo-carrying members, means extending from the interior of the revoluble cylinders to the deck of the ship for pumping water from the revoluble cylinders, an engine room having revoluble protective end plates, and means for operating the hereinbefore described revoluble mem- 65 bers.

11. In a ship, the combination of a cargo 70 carrying drum supported from axial mem- bers, a cylinder revolubly mounted on the axial members to form a protected compartment, water-tight walls separating the aforesaid compartment from other portions of the ship, alined doors for the aforesaid 75 members, means for revolving the revoluble cylinder, an engine room having revoluble protective covering members, and means for revolving said members.

12. In a ship, the combination of revolu- 80 ble cylinders, stationary braced cargo-carrying drums mounted within the revoluble cylinders, axial cylindrical members from which the revoluble cylinders and the braced cargo carrying members are support- 85 ed, reinforced water-tight walls intervening between and separating the cylinders from other portions of the ship, the aforesaid cylinders, drums and walls being constructed in sections to facilitate repairs.

ROBERT W. VAIL.
